UNITED STATES PATENT OFFICE.

JOSEPH LÉON GOBEILLE, OF CLEVELAND, OHIO, ASSIGNOR TO THE ROSSMORE COMPANY, OF NEW YORK, N. Y., A CORPORATION OF NEW YORK.

DESIGN FOR A WATER AND STEAM BOILER SECTION.

SPECIFICATION forming part of Design No. 35,432, dated December 10, 1901.

Application filed November 16, 1901. Serial No. 82,601. Term of patent 7 years.

To all whom it may concern:

Be it known that I, JOSEPH LÉON GOBEILLE, a citizen of the United States, residing at Cleveland, in the county of Cuyahoga and 5 State of Ohio, have invented and produced a new and original Design for a Water and Steam Boiler Section, of which the following is a specification, reference being had to the accompanying drawings, forming part there- 10 of, and in which—

Figure 1 is a plan elevation, and Fig. 2 an edge view or elevation, of my new design.

In the views of the design as thus illustrated there is presented a section or member of a 15 water and steam boiler which is in itself a complete commercial article and in which the leading or material feature of the design is comprised in the entire article as it addresses itself to the eye rather than in any special 20 feature thereof. As a whole the design has certain features combining to produce a novel

and original appearance, and these consist in the arch 2 at its bottom running into legs 3, having feet with openings 4, and the grid-shaped formation 6 in its middle with a central cross-bar 7 and bars 8 in one series in line with openings 9 in the other series, so as to give a staggered effect in the relations of the openings and bars in the several series, as shown, while a relatively broad flat surface 10 at the top, having a central opening 11, completes the face view. 25

What I claim is—

The design of a water and steam boiler section, substantially as shown and described. 30

Witness my hand to the foregoing specification this 17th day of October, 1901.

JOSEPH LÉON GOBEILLE.

Witnesses:

R. B. MOSER,
H. E. MUDRA.
